(57) **CLAIM**

The ornamental design for a floor washing machine, as shown and described.

DESCRIPTION

FIG. 1 is a front elevational view of a floor washing machine showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and right side perspective view thereof;

FIG. 8 is a rear, top and right side perspective view thereof;

FIG. 9 is a front, top and left side perspective view thereof;

FIG. 10 is a rear and left side perspective view thereof;

FIG. 11 is a front, bottom and left side perspective view thereof; and,

FIG. 12 is another front, top and right side perspective view thereof.
